UNITED STATES PATENT OFFICE.

CARLTON N. OGDEN, OF HOUSTON, TEXAS.

VENDING-MACHINE.

1,327,058.

Specification of Letters Patent.

Patented Jan. 6, 1920.

Application filed January 2, 1919. Serial No. 269,227.

To all whom it may concern:

Be it known that CARLTON N. OGDEN, a citizen of the United States, residing at Houston, in the county of Harris and State 5 of Texas, has invented certain new and useful Improvements in Vending-Machines, of which the following is a specification.

This invention relates to new and useful improvements in a vending machine.

10 The object of the invention is to provide a device of the character described, which is adapted for the purpose of vending objects, and may be constructed to vend objects of any desired size or shape.

15 Another object of the invention resides in the provision of a device of the character described, which will automatically lock and which may be operated only through the instrumentality of a coin placed therein.

20 With the above and other objects in view, the invention has particular relation to certain novel features of construction, operation and arrangements of parts, an example of which is given in this specification and 25 illustrated in the accompanying drawings, wherein:

Figure 1, is a vertical sectional view, taken on the line 1—1, of Fig. 2.

Fig. 2, is a transverse sectional view, taken 30 on the line 2—2 of Fig. 1.

Fig. 3, is an enlarged fragmentary vertical sectional view.

Fig. 4, is an enlarged fragmentary transverse sectional view.

35 Fig. 5, is a fragmentary sectional view, taken on the line 5—5 of Fig. 3, and

Fig. 6, is a fragmentary vertical sectional view showing a modified form of the device.

40 Referring now more particularly to the drawings wherein like numerals of reference designate similar parts in each of the figures, the numeral 1, refers to a box-like receptacle, whose lower end is hopper like in form, as at 2. This receptacle is provided 45 to contain articles, as 3, which are to be vended. The receptacle 1, is mounted above and fixed to the oblong casing 4, which is inclosed and has the transverse partition 5, suitably spaced from the ends thereof, and forming the compartments 6 and 6'. Extending lengthwise through the casing 4 is the shaft 7, which is rotatable in suitable 55 bearings in the ends of the casing, and one end of this shaft is turned up, forming the handle 8. Fixed upon the shaft 7, within

the compartment 6, is the cylindric drum 9, which has the oblong peripheral pocket 10, therein, which is normally held in alinement under the hopper 2, through the action 60 of the pull spring 11, one end of which is attached to the top of the casing 4, and the other end of which is attached to the stud 12, projecting out from the shaft 7. Fixed to one end of the compartment 6', is 65 the block 13, whose inner side has a vertical groove 14, and opposite this block and spaced therefrom, is the movable block 15, whose lower end is pivoted to the wall of the compartment, and whose upper end has 70 a transverse arcuate groove 16, through which the pin 17 extends, the outer end of said pin having an enlarged head, and the inner end thereof being secured to the casting wall. The side of this block facing the 75 fixed block 13, has a groove 18, in alinement with the groove 14, said grooves converging downwardly, and forming, in effect, a coin chute. Depending from the top of the casting, is a coin receiver 19, whose lower end 80 alines over said chute. The movable block 15, has a transverse bearing 20, therethrough, in which the latch 21 operates. Within the bearing 20, there is a coil spring 22, one end of which is fastened to the block, and 85 the other end of which presses against the shoulder 23 of the latch, and normally holds one end of said latch projected out toward the block 13. Said projecting end of the latch is beveled upwardly, for a purpose 90 hereinafter explained. The shaft 7 has a laterally projecting finger 24, and when an attempt is made to rotate the shaft 7, without first placing a coin in the device, said finger will engage against the projected end 95 of the latch 21, and lock the shaft against further rotation. When a coin is placed in the receiver, it drops down into the coin chute, and wedges above the latch. If the shaft 7 be now turned, the finger 24 will 100 engage above the coin, and force it downwardly, forcing the upper end of the block 15 backwardly, and overcoming the pressure of the spring 25, against the opposite side of the block 15. The block 15 is thus forced 105 backwardly, until the finger 24 will clear the latch end, and the coin will thereby be forced on down through the chute, and will drop to the bottom of the compartment. The drum 9 will be thereby rotated, carrying the article in the pocket 10 around opposite the discharge opening 26, in the front 110

of the compartment 6, and the same will fall onto the deflector 27, and be discharged from the machine, the periphery of the drum meanwhile holding the other articles against discharge. When the handle 8 is released, the pull of the spring 11 will turn it in the opposite direction, and the finger 24, engaging against the beveled end of the latch, will force it backwardly, overcoming the pressure of the spring 22, thus permitting the finger to pass above the latch, to its original position, and the mechanism will then be in position to vend another article.

In Fig. 6, I have shown the vending mechanism formed to vend another form of article, and it is obvious that the size and shape of the article sold may be varied by varying the size and shape of the pocket 10, in the drum 9.

What I claim is:

1. In a vending machine, a rotatable drum carrying shaft, a coin chute, a pivotally mounted latch support forming one side of said chute, a latch carried by said support and projecting into the chute, a finger projecting laterally from said shaft and provided to engage with said latch to lock the shaft against rotation, said finger being

arranged to move said support through a coin when placed in the chute to withdraw said latch to permit the rotation of said shaft.

2. In a vending machine, a rotatable shaft, a coin chute, one side of which is formed of a pivotally mounted latch support, a yieldably mounted latch carried by said support and projecting into said chute, a finger projecting laterally from said shaft into said chute and provided to engage with said latch when said shaft is actuated in one direction to lock the shaft against rotation, said finger being arranged to move said support through a coin when placed in the chute to withdraw said latch to permit the rotation of the shaft, said finger automatically depressing said latch when said shaft is returned to its original position to return the finger.

In testimony whereof he has signed his name to this specification in the presence of two subscribing witnesses.

CARLTON N. OGDEN.
